United States Patent Office

Des. 218,844
Patented Sept. 29, 1970

218,844

WHEELCHAIR TRAY

Leona L. Davis, 912 S. 17th Ave.,
Yakima, Wash. 98902

Filed Jan. 7, 1970, Ser. No. 20,795

Term of patent 14 years

Int. Cl. D7—99; D24—99

U.S. Cl. D44—10

FIG. 1

FIG. 2

FIG. 1 is a top perspective view of a wheelchair tray showing my new design, with the box cover open; and

FIG. 2 is a bottom perspective view from another angle, with the box cover closed.

I claim:

The ornamental design for a wheelchair tray, substantially as shown and described.
